J. S. ANDERSON

TABLE CASE

Filed Sept. 13, 1922

UNITED STATES PATENT OFFICE.

JOHN S. ANDERSON, OF JAMESTOWN, NEW YORK.

TABLE CASE.

Application filed September 13, 1922. Serial No. 587,925.

To all whom it may concern:

Be it known that I, JOHN S. ANDERSON, a citizen of the United States, residing at Jamestown, in the county of Chautauqua and State of New York, have invented certain new and useful Improvements in Table Cases, of which the following, taken in connection with the accompanying drawings, is a specification.

10 This invention relates to an improvement in a table case and more particularly to the combination of a foldable table, and foldable stools, these parts being so formed that when folded the case forms a compact, easily 15 carried receptacle having the appearance of the usual suitcase.

The chief object of this invention is to provide a case comprising a table foldable along the center line with foldable and extensible 20 legs; which table when opened constitutes a firm support and when folded forms a closed receptacle; a plurality of foldable stools that are carried within the receptacle formed by the table and a box that 25 may be used for holding lunch, or table utensils, or for other purposes if desired also within the receptacle.

A further object is to provide a foldable table having foldable and extensible legs 30 with a simple but firm rigid means for folding the legs extended.

Other objects will appear from an examination of the following description taken in connection with the accompanying drawing 35 which forms a part thereof and in which—

Fig. 1 is a plan view of the inner side of the opened table, the legs being folded in place and the stools and box assembled.

40 Fig. 2 is a cross sectional view of the opened table with the legs unfolded and extended to support the table.

Figs. 3 and 4 are cross sectional views taken along the lines 3—3 and 4—4 of Fig. 1 illustrating the compact manner in which the parts are assembled.

45 Figs. 5 to 9 inclusive are various detail views of the manner in which the legs are hinged to the table and in which the leg sections are connected and

Fig. 10 is a side elevation of one of the stools opened for use.

The table case here shown provides an 50 easily carried compact outfit that can be placed in an automobile without requiring a great amount of space and which when

opened out provides a table on which a picnic lunch can be spread and four stools for the participants. This outfit obviates the necessity previously present of carrying the 60 table and stools as separate elements which is objectionable even though the elements are individually foldable.

Referring to the drawing the numeral 10 is used to designate a case made in accordance with this invention and comprising a table 11, four stools 12 and a box 13.

The table 11 consists of two identical sections 14, 14, joined by hinges 15 and each made of a rectangular frame 16 to which is secured a top 17. Pivoted to the frames 16 at the four corners of the table are

legs 18 having an upper metal section 19 of channelled cross section and a lower section 20 which is preferably of wood, as shown in the drawing and foldable into the channel of the upper section. Rigidly secured at the corners of the table are brackets 21 having parallel flanges 22 one of which is attached to the frame 15. Through each pair of flanges 22 is passed a bolt 23 which also passes through inclined slots 24 in the upper section 19 of the leg as best illustrated in Figs. 6 and 7. By reason of the inclination of the slots 24 the legs when at right angles to the table, see Fig. 6, may be forced up into the bracket 21 until the face of the section 19 contacts therewith. In this position it is of course impossible for the legs to move relative to the table but by pulling it 55 down the section 19 leaves the inner face of the bracket 21 so that when the bolt 23 engages the upper ends of the slots 24 the leg can be swung at right angles into the position shown in Fig. 1.

The lower section 20 of the leg 18 is made smaller so that when the leg is folded it will lie in the channel 26 of the upper section 19. Adjacent the lower ends of the flanges 22 are formed slots 25 inclined, like the slots 24, toward the central portion 28 of the upper section. The lower section is hinged to the upper section by pins 27 and when the pins are at the bottom of the slots it swings freely. When, however, the lower section after being brought into alignment with the upper section is forced upwardly into the channel 26, it is carried against the central portion 28 and consequently held 60 against any swinging movement.

The stools 12 consist of two outer legs 30 hinged at 31 to two inner legs 32. The

outer legs are joined at the upper end by a cross bar 33 and the inner legs are similarly connected by a cross bar 34. The inner legs 32 are made slightly shorter than the outer legs 30 so that when the stool is folded the cross bar 34 will lie below the cross bar 33 so that the inner legs will lie entirely within the outer legs. Across the upper ends of the legs is secured flexible material 35 which is fastened to the cross bars 33 and 34. Metal plates 36 and 37 are attached to the legs 30 and 32 respectively to hold the material 35 in position. The plate 36 also acts to limit the folding 15 of the stool by its contact with the upper ends of the inner legs 34.

In assembling the parts the lower sections 20 of the legs 18 are folded into the channels of the sections 19 and the legs are folded down into the spaces bounded by the frames 15. The stools 12 are then collapsed and assembled in pairs, the legs on one side of each stool being inserted between the plates 36 and 37 of the other 25 stool so that each pair may be placed in one of the table sections 14. Each pair of stools 12 when so assembled provides a rectangular space 39 and in the space of one pair is placed the box 13 which is preferably twice as high as the frame 15 (see Figs. 3 and 4) so that it will project into the space 39 of the other pair when the table with its contents is folded. For convenience in carrying, a handle 40 is provided the sections 14 held together by latches, not shown, or any other desired 35 means.

While one embodiment only has been shown and described, I am not to be limited 40 thereby since it is obvious that other embodiments can be made without departing from the spirit and scope of this invention as set forth in the following claims.

Having thus set forth my invention, what 45 I claim as new and for which I desire the protection of Letters Patent is:

1. A table case comprising a folding table a plurality of stools and a box said table consisting of two sections hinged together, each section comprising a rigid rec-

tangular frame to which a portion of the table top is secured, brackets at the outer corners of said frames, legs pivoted to said brackets each leg being in two sections the upper section being of channelled cross section and the lower section being pivoted to the lower end of said upper section whereby the lower section may be swung on said pivot into the channel of said upper section, the length of the upper section of said legs being somewhat less than the width of said table sections whereby the legs may be folded across the ends of said table sections, to provide rectangular spaces for foldable stools and a box said stools being so formed and assembled that the legs thereof form a rectangular space in which said box may be received.

2. A table case comprising a folding table a plurality of stools and a box said table consisting of two sections hinged together, each section comprising a rigid rectangular frame to which a portion of the table top is secured, brackets at the outer corners of said frames, legs pivoted to said brackets each leg being in two sections the upper section being of channelled cross section and the lower section being pivoted to the lower end of said upper section whereby the lower section may be swung on said pivot into the channel of said upper section, the length of the upper section of said legs being somewhat less than the width of said table sections whereby the legs may be folded across the ends of said table sections, to provide rectangular spaces for foldable stools and a box said stools being so formed and assembled that the legs thereof form a rectangular space in which said box may be received, the table legs and collapsed stools being of less height than said rectangular frame and said box being double the height of said frame whereby when the table case is collapsed the box will fill the rectangular spaces provided by the legs of said stools.

In testimony whereof I have affixed my signature.

JOHN S. ANDERSON.
